UNITED STATES PATENT OFFICE.

EDWARD H. DEWEY, OF CHICOOPEE FALLS, MASSACHUSETTS, ASSIGNOR OF ONE-FOURTH TO FRANK A. CHAMPLIN, OF EAST LONGMEADOW, MASSACHUSETTS, AND ONE-FOURTH TO DANIEL F. MORIARTY, OF HOLYOKE, MASSACHUSETTS.

VALVE-SPRING COMPRESSOR.

Application filed December 13, 1921. Serial No. 521,974.

To all whom it may concern:

Be it known that I, EDWARD H. DEWEY, a citizen of the United States of America, and a resident of Chicopee Falls, in the county of Hampden and State of Massachusetts, have invented a new and useful Valve-Spring Compressor, of which the following is a specification.

My invention relates to improvements in tools or implements for use in detaching poppet-valves of internal-combustion engines, and consists of a double-headed ratchet bar or lever, the heads of such lever being bifurcated and provided with upturned ends, a hook pivotally connected with said lever, and a pawl pivotally connected with said hook, the pivotal connections in each case being adjustable, and the parts and members being of peculiar construction, all as hereinafter set forth.

The primary object of my invention is to produce a comparatively simple and inexpensive, yet strong, durable, and convenient compressor for the valve-springs of internal-combustion engines, which is capable of being applied to, at any suitable angle relative to the sides of, the engine, by hooking a member of such compressor over the manifold of such engine, without swinging or slipping out of engagement with the cup at the base of the valve spring.

Another object is to provide a device of this character which can readily be adjusted to meet different conditions, and so that it will compress the spring evenly or uniformly.

Other objects and advantages will appear in the course of the following description.

I attain the objects and secure the advantages of my invention by the means illustrated in the accompanying drawings, in which—

Figure 1 is a top plan of a valve-spring compressor which embodies a preferred form of my invention; Fig. 2, a side elevation of said compressor, and, Fig. 3, a top plan of a modified form of construction.

Similar reference characters designate similar parts throughout the several views.

Referring first to the preferred form of the invention as illustrated in the first two views, it will be seen that the same comprises a bar or lever 1 having bifurcated heads or forked terminals 2 and 3, the outer

ends of which terminals are turned upwardly to form lugs 4, and said lever also having on the upper edge thereof two sets of ratchet teeth 5; a hook 6 pivotally connected at the base with said lever; and a pawl 7 pivotally connected at the upper terminal with said hook intermediate of the ends thereof.

Preferably the lever 1, instead of being straight, extends upwardly in both directions from the transverse center thereof, or has two sections that form an obtuse angle with each other, substantially as shown. This is for the purpose of enabling the implement to be used on a car where the fenders are at an acute angle to the frame, and where it would be difficult or impossible to employ the implement if the lever were straight.

The head 2 is wider than the head 3 of the lever 1, and the opening or slot, as 8, in said first-named head is correspondingly wider than the slot, as 9, in said second-named head, so that the former is adapted for large valve-stems and tappets, and the latter for small valve-stems and tappets.

The teeth 5 on each side of the transverse center of the lever 1 are directed or inclined toward the vertical plane of such center, and all are adapted to be engaged by the free terminal of the ratchet 7, in the manner hereinafter explained.

There is a plurality of transverse openings 10 through the lever 1 each side of the aforesaid transverse center, and a screw 11, which serves as the pivot between the hook 6 and said lever, is adapted to be received in any of said openings. At the bottom of the hook 7 is a clevis or fork 12 that is adapted to fit over the lever 1 and the teeth 5, and to be connected with said lever by the screw 11. There is a plurality of openings 20 in the arms of the fork 12. A nut 13 is provided to retain the screw 11 in place after being passed through one pair of openings 20 in the arms of the fork 12 and one of the openings 10 in the lever 1. Thus it is seen that the pivotal connection between the hook and lever can be changed or adjusted to meet different conditions.

There is a plurality of transverse openings 14 through the hook 6 intermediate of the ends thereof, and a screw 15, which serves as the pivot between the pawl 7 and

said hook, is receivable in any of said openings. At the upper end of the pawl 7 is a clevis or fork 16 that is adapted to fit over the hook 6 adjacent to the openings 14, and 5 to be connected with said hook by the screw 15. The screw 15 passes through the fork 16, the arms of which are perforated to receive said screw, and one of the openings 14. A nut 17 is provided to hold the screw 15 in 10 place. By changing the location of the screw 15, or transferring it from one opening 14 to another, the pivotal connection between the pawl 7 and the hook 6 is changed. Thus provision is made for changing or adjusting the position of the pivotal connection 15 between the pawl 7 and the hook 6 to meet different conditions involved in the use or application of the compressor.

When the hook 6 is connected with the 20 lever 1 in the manner illustrated, the application or operation of the compressor is as follows: The curved upper terminal of the hook 6 is placed over the manifold, the head 3 is introduced beneath the cup of the spring 25 to be compressed, and the bar 1 is grasped at the terminal opposite to said head and forced downwardly, with the screw 11 as a fulcrum for said bar, until the spring is sufficiently compressed. As this operation 30 takes place the pawl 7 swings on the screw 15 and the free terminal of said pawl moves over the left-hand set of teeth 5 toward the transverse center of the lever 1, and finally 35 engages one of said teeth, thus locking the parts and retaining the spring under compression, the movement of the pawl being automatic. The valve-stem at this time is in the slot 9, and the lugs 4 at the outer end of the head 3 engage the outer edge of the 40 cup, which latter is seated on said head, and so prevent the latter from slipping out from beneath said cup, either during the compressing operation or while the spring is held under compression for the removal of 45 the valve. When it is desired to remove the compressor, it is simply necessary to depress the free terminal of the lever 1 sufficiently to enable the pawl 7 to be released from the tooth 5 with which it is engaged, swing said 50 pawl upwardly on the screw 15, permit said lever to swing on the screw 11 in the direction and to the extent required to release the spring, and remove the hook 6 from the manifold.

55 The manifold, valve spring, cup, and other engine parts and members herein mentioned are too well known to need to be illustrated, and the application and operation of my compressor will be clearly understood without such illustration.

60 With the hook 6 connected with the lever 1 in the manner herein shown and described, the former does not turn or twist when placed in position over the manifold, so that 65 it is possible to manipulate this implement

with one hand, especially in view of the fact that the pawl 7 automatically engages the teeth 5 as the free end of the lever 1 is depressed.

If it be desired to use the head 2 instead 70 of the head 3, the nut 13 is removed from the screw 11, the latter is withdrawn, the hook 6 is turned about and its fork 12 placed over the lever 11 adjacent to one of the openings 10 at the left of the transverse 75 center of said lever, said screw is reinserted in said fork and passed through the required opening, and said nut is returned to place on the screw. The pawl 7 is now in position to engage the teeth 5 at the right of the 80 aforesaid center. The operation of the compressor under the new arrangement is substantially the same as that already described.

It is clear from the foregoing, not only 8 that any required adjustment between the 80 hook 6 and the lever 1 by locating the screw 11 in different openings 10 in a set and between the pawl 7 and said lever by locating the screw 15 in different openings 14 can be 85 made, but that the parts are interchangeable 9 so that either end of said lever can be employed.

In the modification illustrated in Fig. 3, 9 a bar 18 is shown which is wider than the bar 1 and has a longitudinal slot 19 therein between the heads 2 and 3, and the hook 6 is made without the fork 12, but instead has a perforated terminal that is receivable in said slot. Otherwise this construction is similar to the first, and the operation of the same is not materially different.

More or less change in the shape, size, construction, and arrangement of some or all of the parts of this device may be made without departing from the spirit of my invention or exceeding the scope of what is claimed.

What I claim as my invention, and desire to secure by Letters Patent, is—

1. A valve-spring compressor comprising a forked and serrated lever, a manifold-engaging hook pivotally connected with said lever, and a pawl pivotally connected with said hook and adapted to engage the serrations in said lever.

2. The combination, in a valve-spring compressor, with a lever having forked terminals with upturned lugs at their ends, and provided with two sets of ratchet teeth on opposite sides of the transverse center of said lever, of a manifold-engaging hook, means to connect said hook pivotally with said lever either side of said center, and a pawl pivotally connected with said hook and adapted to engage the teeth in the set that is on the opposite side of said center to that where said hook is pivotally connected with said lever.

3. The combination, in a valve-spring compressor, with a lever having forked ter-

minals with upturned lugs at their ends, and provided with two sets of ratchet teeth on opposite sides of the transverse center of said lever, of a manifold-engaging hook, 5 means to connect said hook pivotally with said lever either side of said center, a pawl adapted to engage the teeth in the set that is on the opposite side of said center to that where said hook is pivotally connected 10 with said lever, and adjustable means pivotally to connect said pawl with said hook.

4. The combination, in a valve-spring compressor, with a lever consisting of two sections that form an obtuse angle with 15 each other, said lever having forked terminals with upturned lugs at their ends, and provided with two sets of ratchet teeth on opposite sides of the transverse center of said lever, of a manifold-engaging hook, 20 means to connect said hook pivotally with said lever either side of said center, and a pawl pivotally connected with said hook and adapted to engage the teeth in the set that is on the opposite side of said center to 25 that where said hook is pivotally connected with said lever.

5. The combination, in a valve-spring compressor, with a lever provided with forked terminals having upturned ends, and 30 also, on opposite sides of the transverse center of said lever, with ratchet teeth on the upper edge and openings which extend through the sides thereof, of a manifold-engaging hook, pivotal means for connecting the base of said hook with said lever 35

through any of said openings, and a pawl pivotally connected with said hook intermediate of its ends, and adapted to engage any of said teeth.

6. A valve-spring compressor comprising 40 a forked and serrated lever having a longitudinally-extending slot intermediate of the ends thereof, a manifold-engaging hook having the lower terminal inserted in said slot and pivotally connected with said lever, and 45 a pawl pivotally connected with said hook and adapted to engage the serrations in said lever.

7. The combination, in a valve-spring compressor, with a lever having forked terminals with upturned lugs at their ends, and a longitudinally-extending slot intermediate of such ends, and provided with two sets of ratchet teeth located on opposite sides of the transverse center of said lever, said teeth 55 being formed on the upper longitudinal edges of the portions of the lever separated by said slot, of a manifold-engaging hook having its lower terminal in said slot, means to connect said hook pivotally with said 60 lever either side of said center, and a pawl pivotally connected with said hook and adapted to engage the teeth in the set that is on the opposite side of said center to that where said hook is pivotally connected with 65 said lever.

EDWARD H. DEWEY.
